(57) **CLAIM**

The ornamental design for an arch support insole as shown and described.

DESCRIPTION

FIG. 1 is a perspective view of an arch support insole for a left foot showing my new design.

FIG. 2 is another perspective view thereof;

FIG. 3 is a right side view thereof;

FIG. 4 is a left side view thereof;

FIG. 5 is a front sideview thereof;

FIG. 6 is a rear view thereof;

FIG. 7 is a top plan view thereof;

FIG. 8 is a bottom plan view thereof; and,

FIG. 9 is an enlarged view of portion 9 shown in FIG. 1. The arch support insole for a right foot is a mirror image of the insole for the left foot shown.

The dash-dash broken lines in the drawings depict portions of the arch support insole that form no part of the claimed design. The dot-dash broken lines represent boundary of the enlarged portion and form no part of the claimed design.
